UNITED STATES PATENT OFFICE

114,386

DESIGN FOR A DECK OF PLAYING CARDS

John Caldwell Hampshire, New York, N. Y.

Application January 10, 1939, Serial No. 82,267

Term of patent 14 years

To all whom it may concern:

Be it known that I, John Caldwell Hampshire, a subject of the King of Great Britain, residing at New York, county and State of New York, have invented a new, original, and ornamental Design for a Deck of Playing Cards, of which the following is the specification, reference being had to the accompanying drawing, forming part thereof.

The drawing shows a face view of the ace, king, queen, jack, 10, and 7 which are typical of the complete deck of fifty-two cards of my new design.

The drawing is shaded to show contrasting appearance.

I claim:

The ornamental design for a deck of playing cards, as shown and described.

JOHN CALDWELL HAMPSHIRE.
